UNITED STATES PATENT OFFICE.

HIRAM MENDENHALL AND ROBERT G. PING, OF AUDUBON, IOWA.

IRONING-BOARD CABINET.

950,397.

Specification of Letters Patent. Patented Feb. 22, 1910.

Application filed April 12, 1909. Serial No. 489,327.

To all whom it may concern:

Be it known that we, HIRAM MENDENHALL and ROBERT G. PING, citizens of the United States, residing at Audubon, in the county 5 of Audubon and State of Iowa, have invented a certain new and useful Ironing-Board Cabinet, of which the following is a specification.

The object of our invention is to provide 10 an ironing board cabinet of simple, durable, and inexpensive construction, so arranged that when in a folded position, it will occupy a minimum of space and also so arranged that the ironing board proper will 15 form the major portion of the front of the cabinet when in its folded position to thereby utilize the ironing board for the double purpose of an ironing board and a front member for the cabinet.

20 A further object is to provide improved means for supporting the ironing board in different positions of adjustment.

25 A further object is to provide improved means for securing a fabric cover to the ironing board.

Our invention consists in the construction, arrangement, and combination of the various parts of the device whereby the objects contemplated are attained, as hereinafter more 30 fully set forth, pointed out in our claims, and illustrated in the accompanying drawings, in which—

Figure 1 shows a perspective view of the complete device embodying our invention in 35 position for use as an ironing board. Fig. 2 shows a front elevation of same in a folded position. Fig. 3 shows a vertical, central sectional view of a device embodying our invention with the ironing board and the sleeve ironing board in extended positions 40 ready for use. The dotted lines in said figure show the ironing board at its upper limit of movement. Fig. 4 shows a similar view with the ironing board and the sleeve 45 ironing board in their folded positions. Fig. 5 shows a detail, sectional view illustrating the means for securing the fabric cover to the ironing board.

50 Referring to the accompanying drawings, we have used the reference numeral 10 to indicate the base of the cabinet, 11, the upright sides, and 12, the top. The ironing board proper forms the front of the cabinet, and, hence, it is not necessary to provide a 55 door or other front. However, the shape of the ironing board is such that it will not

wholly cover the front and we, therefore, provide two front corner pieces 13 permanently fixed to the sides and top. At the rear of the cabinet are three cross pieces 14, 15, and 16, for purposes hereinafter made clear, and on the front edges of the side pieces, near the lower ends, are the strips 17, for purposes hereinafter made clear.

On the inner face of each side piece is a 65 vertical groove 18, and near the central portion of each side piece is a metal plate 19 having two notches 20 therein, one notch being adjacent to the cross piece 15 and the other adjacent to the cross piece 16.

70 The ironing board proper comprises a body portion 21 having its outer end tapered and also having a flange or rib 22 projecting laterally from its edges, except at its inner end. The said inner end is designed to 75 freely slide up and down between the sides of the cabinet and the said flange or rib is designed to overlap the front edges of the sides of the cabinet and the inner edges of the front members 13 to thereby form a 80 complete closure for the front of the cabinet. The strips 17 are designed to fit tightly 85 against the sides of the board below the flange or rib when the board is in its closed position. A latch device 23 is pivoted to the top 12 and is designed to normally stand in position extended downwardly over the upper end of the ironing board to thereby hold it in its closed position, and said latch device is also capable of being swung upwardly to permit the ironing board to move 90 outwardly.

95 Fixed to the upper surface of the ironing board, near its inner end, is a cross piece 24 projecting beyond the sides of the ironing board and designed to fit into the grooves 18 and also to enter the notches 20; and on the outer surface of the ironing board, near its central portion is a hinged support 25 designed to enter notches 26 100 formed in an upright 27 at the lower rear portion of the cabinet, the upper end of said upright being attached to the cross-piece 14 and the lower end to the base 10. A chain 105 28 is provided to connect the ironing board and the support and said support is preferably formed with a groove 29 to receive said chain so that the support may lie flat against the ironing board when the ironing board is in its upright position and when 110 in said position, the chain will lie in said groove.

We have also provided means for detachably connecting a fabric covering with the ironing board as follows: In the edges of the ironing board, we have formed grooves designed to receive the angular strips 30. We attach the fabric by placing it over the top of the ironing board and in position overlapping said grooves and we then force the strips 30 into the grooves thus causing the fabric to be stretched and to be firmly supported in said grooves by the strips. In this way, a new fabric can be quickly and easily substituted for an old one without the use of tacks or other fastening devices.

The sleeve ironing board comprises a body portion 31 connected by a hinge 32 with the cross piece 16. It is provided with a hinged supporting brace 33 designed to enter a notch 34 in the cross piece 16. In this way, the sleeve ironing board may be supported in a horizontal position above the main ironing board and, when not in use, the sleeve ironing board may be raised to the position shown in Fig. 4, and when the main ironing board is in position in the front of the cabinet, the sleeve ironing board will be wholly concealed and protected thereby.

It is obvious that the entire device may be constructed with a minimum of cost and by the use of a minimum of material, because the cabinet itself comprises only the narrow side uprights and the top and bottom while the ironing board proper forms the major portion of the front and takes the place of a door for the front.

Assuming that the cabinet is in the position shown in Fig. 4, then if it is desired to adjust the parts to the position shown in Fig. 3, the operator first releases the latch device 23, and then swings the upper end of the ironing board outwardly a short distance. He then bodily raises the ironing board to position with the cross piece 24 thereof adjacent to the lower one of the notches 20. During this raising movement, the lower end of the ironing board will be guided in the slots 18 by the ends of the cross piece 24. The operator then moves the inner end of the ironing board rearwardly until the cross piece 24 rests in the rear lower portion of the notch 20. When in this position, the rear end of the ironing board extends beneath the cross piece 15, and the supporting brace 25 will rest in one of the notches 26 and thus firmly hold the outer end of the ironing board in a horizontal position. Obviously, the ironing board can be readily and easily raised to the position shown by dotted lines in Fig. 3, so that the operator may have the board at any desired height.

The sleeve ironing board can be easily moved to its position for use as shown in Fig. 3. When it is desired to close the cabi-

net, the operator first closes the sleeve ironing board. He then raises the inner end of the main ironing board far enough to permit the cross piece 24 to move out of the notch 20 into the groove 18, and then permits the lower end of the ironing board to slide down in said groove until it rests upon the bottom of the cabinet; he then closes the ironing board against the upper portion of the cabinet and the flange or rib 22 at the edge of the ironing board will overlap the parts 13 of the front, and the edges of the sides, and thus form a tight joint all around the ironing board to completely close and protect the interior of the cabinet and the upper surface of the ironing board itself from dust and dirt.

We claim as our invention.

1. An improved ironing board cabinet, comprising a frame open at its front, said opening extending from a point near the bottom to a point near the top of the cabinet, an ironing board slidingly mounted in the cabinet and capable of being moved from substantially horizontal position near the center of the opening in the cabinet to a vertical position, in which latter position it will serve as a closure for the opening in the front of the cabinet, said ironing board being provided with flanges at its sides designed to overlap the sides of the opening in the front of the cabinet.

2. An improved ironing board cabinet, comprising a frame open at its front and having corner pieces at the upper corners of the front and also having upright strips at the lower edges of the sides of the frame at the front thereof, and an ironing board capable of up and down movement relative to the cabinet and having one end shaped to enter between the sides of the cabinet, and its body portion shaped to fit into the opening in the front of the cabinet, and flanges on the sides of the ironing board designed to overlap the edges of the opening in the front, said flanges near the bottom of the board being cut away, and said strips on the side edges of the frame being designed to fit into the cut away portions of the flanges when the ironing board is in position for closing the front of the cabinet.

3. An improved ironing board cabinet, comprising a frame having sides, top and bottom pieces, cross pieces at the rear of the frame, front pieces at the upper portion of the frame of such shape as to form an opening in the front of the frame of the size and shape of an ironing board, said side pieces being provided with vertical grooves, notched plates secured to said side pieces, an ironing board shaped to fit into the open front of the cabinet, a flange or rib on the ironing board to overlap the front of the cabinet around the opening, a cross piece secured to the upper portion of the

ironing board to enter the grooves and notches in the sides, the adjacent end of the ironing board being designed to engage said cross pieces in the frame when the cross 5 piece of the ironing board is in the notches and the ironing board is in a horizontal position, a supporting brace hinged to the ironing board, a chain for connecting it with the ironing board, said brace being formed with 10 a groove to receive said chain when the

brace is folded against the ironing board, and a notched upright in the frame to receive the supporting brace.

Des Moines, Iowa, March 24, 1909.
